(57) **CLAIM**

The ornamental design for an inspection door with vent hole for flask-less molding machine, as shown and described.

DESCRIPTION

FIG. 1 is a perspective view of an inspection door with vent hole for flask-less molding machine of the present invention. FIG. 2 is a front view of the inspection door with vent hole for flask-less molding machine of FIG. 1.

FIG. 3 is a rear view of the inspection door with vent hole for flask-less molding machine of FIG. 1.

FIG. 4 is a top plan view of the inspection door with vent hole for flask-less molding machine of FIG. 1.

FIG. 5 is a bottom view of the inspection door with vent hole for flask-less molding machine of FIG. 1.

FIG. 6 is a right side view of the inspection door with vent hole for flask-less molding machine of FIG. 1.

FIG. 7 is a left side view of the inspection door with vent hole for flask-less molding machine of FIG. 1.

FIG. 8 is a sectional view taken along the line 8-8 of the inspection door with vent hole for flask-less molding machine of FIG. 2.

FIG. 9 is a sectional view taken along the line 9-9 of the inspection door with vent hole for flask-less molding machine of FIG. 2; and,

FIG. 10 is a reference perspective view of the inspection door with vent hole for flask-less molding machine of FIG. 1 in use, wherein the inspection door is attached to a lower end opening part of a lower molding sand tank of a flask-less molding machine for molding a cast, which is for illustrative purpose only and form no part of the claimed design.

(Continued)

The features shown in broken lines depict environmental subject matter and illustrate portions of the inspection door with vent hole for flask-less molding machine and form no part of the claimed design.
